CURRENT COLLECTOR

Alfred J. Mosley, Cleveland, Ohio, assignor to
 National Bronze & Aluminum Fdry. Co., Cleve-
 land, Ohio, a corporation of Ohio

Application February 14, 1949, Serial No. 76,359

5 Claims. (Cl. 191—59.1)

1

This invention relates to electrical current collecting devices, more particularly to slider shoes such as are employed on trolley poles used on electric busses, street cars, and the like.

Current collectors or slider shoes are replaced or rebuilt from time to time on busses and street cars because of the wear that occurs in use. Such shoes or collectors are designed to minimize wear on the conductors or trolley wires of transit systems, not only because of the great expense involved in replacing trolley wires, but also because of the disruption to the transit system caused by discontinuance of service for trolley wire replacement.

It is therefore one of the principal objects of the present invention to provide a generally improved collector shoe or trolley slide of the type employing a suitable wear resistant insert or wire contacting brush, the collector shoe being simple in design and construction for economical mass production as by casting so that when renewal is necessary, it is feasible to replace the entire shoe and discard the worn one.

Another object is to provide a rugged, long wearing collector shoe relatively light in weight and substantially free of internal or structural strains, such characteristics being achieved without objectionably increasing the relative wear on trolley wires. Preferentially the slider includes a wear insert and a one piece holder or frame cast about the insert, the frame incorporating simple wiper or scraper means to remove objectionable foreign material from trolley wires in advance of the insert, thus preventing the movement of abrasive particles between such wires and the wear insert. More specifically, the invention seeks to provide a unitary slider shoe incorporating an elongated carbon wear block or brush, preferably of rectangular transverse section, embedded in a one piece cast metal body or frame of relatively lightweight construction.

Another object is to provide a current collector shoe of the carbon insert type suitable for manufacture by high speed casting of light metal alloys.

A further object is to provide a lightweight collector shoe capable of carrying relatively high energy electrical current without objectionable heating, yet being cheap to make and having a brush insert for long wear.

Other objects and advantages relate to certain details of construction and combinations and arrangements of parts, as set forth in the following detailed description of the invention made in connection with the accompanying drawings form-

2

ing a part of the specification. Like parts throughout the several views are indicated by the same numerals of reference.

In the drawings:

- 5 Figure 1 is a side elevational view, with parts broken away and removed, of the upper or head end of a trolley pole structure showing the replaceable collector shoe of the present invention mounted thereon;
- 10 Fig. 2 is an end elevational view of the collector shoe of Fig. 1;
- 15 Fig. 3 is a top plan view of the collector shoe;
- Fig. 4 is a transverse sectional view taken substantially on the line indicated at 4—4 of Fig. 1, the trolley pole head being omitted;
- 20 Fig. 5 is an elevational view, partly in section and with parts removed, showing a modified form of collector shoe; and
- 25 Fig. 6 is an end elevational view partly in section and with parts removed of the trolley shoe shown in Fig. 5.
- The collector shoe or slider of the present invention is suitable for mounting on conventional types of trolley poles, a representative and simplified trolley pole head being shown in Fig. 1. The assembly includes a head member 1 suitably secured on the upper end of the trolley pole and formed with a yoke or harp 2 which carries a transverse pivot bolt 3 for tiltably mounting a carrier or tilt block 4. The structure desirably includes conventional means, not shown, permitting the slider shoe to turn about a vertical axis which permits lateral or side to side movement of the trolley pole under the trolley wire.
- 30 35 The replacement shoe or current collector itself comprises an elongated wear block or insert 5 formed as by pressure molding of carbon or carbonaceous material of graphitic character. This block may be suitably treated or impregnated in a conventional manner with the customary metal, plastic, or other friction reducing and binding materials. Although various cross-sectional shapes may be employed, it is preferable to make the wear insert of substantially uniform rectangular transverse or cross section from end to end. Desirably the block is of greater height than width for long life.
- 40 45 Mounting the wear insert or carbon element on the top flat surface of the tilt block 4 and protecting the carbon element against damage from shock and impact is a guard frame or body formed, preferably in one piece, as by casting of a metal such as brass, bronze or aluminum and its alloys. The cast body is designed with particular reference to the shrinkage that occurs in metal such

as aluminum, upon cooling from the molten state. Considerable difficulty has been encountered in casting carbon and graphitic wear inserts in aluminum because of the stresses imposed on such inserts during the cooling of the cast metal body. In the present arrangement, the cast body is formed of holding and supporting portions which, though relatively thick in section to provide the desired strength, and though so disposed, arranged and connected as to interlockingly hold and embrace the insert, do not impose undesirable stresses or forces on such insert upon cooling from the molten state. The cast metal parts or elements comprising the body may be connected, preferably integrally, by relatively thin portions for embracing and confining the major portions of the wear insert.

A suitable arrangement for the frame comprises a pair of spaced substantially U-shaped stirrups arranged in parallel relation, each stirrup having uprights 6 integrally connected by bottom or cross elements 7. The stirrups receive the ends of the wear block 5, sides 9 of the wear block at the ends of the latter being embraced by the upright portions 6 of the stirrups, and portions of bottom 10 of the wear block at the ends of the latter resting on the cross or integral connecting portions 7 of the stirrups. The upper ends of the stirrup uprights 6 are connected, preferably integrally, by longitudinally extending guide elements 8. The guide elements include angularly disposed end portions 11 presenting inclined or sloping edges 12 which aid in moving the contactor shoe across switches, crossing plates, and the like. Preferably, the guide elements 8 are divergently arranged above the wear block 5, as shown in Fig. 2, providing a tapered channel to receive and confine the trolley wire which is to be received and engaged in groove 19 of the wear block 5.

Foreign material such as dust, dirt and the like, collecting on trolley wires, is frequently dislodged by current collectors and trolley shoes moving along thereunder. Such material of a hard or gritty nature, when caught and held in the open top channel of a collector shoe, is objectionable because of abrasion to the trolley wire and to the shoe and interference with electrical conductivity. The construction of the present collector or trolley shoe leaves substantially the entire margin or periphery of top surface 14 of the carbon block 5 substantially open and unobstructed laterally so that particles of foreign material dropping into the trolley wire channel are readily discharged not only through the relatively narrow channel ends but also laterally along substantially the entire length of the carbon block. In the present arrangement the guide elements 8 are disposed wholly above the plane or level of the top 14 of the wear block providing elongated lateral openings 15 below bottom edges 16 of the guide elements. Although these elongated clearance openings may be of less extent, they preferably are continuous along substantially the major portion of the upper edge corners of the carbon wear block or insert.

Across the ends of the shoe or collector the stirrup uprights 6 are connected as by integral relatively thin webs 17 which are disposed flatwise against end faces 18 of the carbon wear block 5. Although the end webs 17 may be of any desired height relative to the carbon wear block, it is preferable to make them of substantially the same height as the wear block so as to move along the trolley wire closely adjacent or

in contacting relation to the latter for wiping the trolley wire free of dirt and foreign material in advance of the carbon block. This feature is particularly advantageous in localities where ice forms on the trolley wires, since the relatively tough brass or aluminum of the webs 17 removes depending ice particles in advance of the more fragile or brittle carbon block.

Along the sides of the collector relatively thin web portions 20 connect the stirrup uprights 6 and are preferably integral with the latter. These connecting webs are disposed flatwise against the central portions of the block side faces 9 and may be smooth surfaced, although preferably they are formed with a multiplicity of relatively thin cooling and reinforcing ribs 21. The ribs 21, which may be sheet metal inserts or, as shown, cast integrally with the webs and stirrups in the formation of the collector shoe, extend longitudinally of the side webs substantially from end to end thereof, being joined or connected to the stirrup uprights 6. In the aggregate, the areas of the block faces contacted by the relatively thin connecting webs are greater in extent than the areas contacted by the relatively thick sectioned frame elements.

In mounting the collector or trolley shoe on the tilt block 4 of the trolley pole, conventional arrangements may be employed. The illustrated arrangement comprises integral ears or lugs 22 and 23 connected to or cast integrally on the bottom cross elements 7 of the frame stirrups. The ear 22 includes an offset portion which is receivable against an undercut face 24 on one end of the tilt block 4. The lug 23 is drilled and threaded to receive an angularly disposed locking screw 25 arranged to bear against an angularly disposed face 26 on the other end of the tilt block. When the screw 25 is tightened against the tilt block face, the bottom face 10 of the carbon block 5 and bottom edges 27 of the side webs 20 are drawn snugly against the flat upper surface of the tilt block 4, effecting good electrical connection therewith.

In applications requiring the transfer of large electrical currents, the collector shoe described is particularly advantageous by reason of the cooling action of the ribs or vanes 21 which travel longitudinally through the atmosphere. Heat developed in the carbon block 5 by reason of the conductivity of electrical current therethrough is taken up all along its sides by the closely embracing relatively rapid heat conducting metal of the cast body and is quickly conducted into the cooling vanes 21 for dissipation to the atmosphere. Thus, overheating of the carbon and metal of the collector shoe is avoided.

In applications requiring a less rugged construction, or where less electrical energy is to be conducted, or where other considerations control, the modification illustrated in Figs. 5 and 6 may be employed. In these figures, parts or components of the structure that are the same as in the embodiment of Figs. 1 through 4 are indicated by the same reference numerals. The end webs 17 are omitted or reduced in height at both ends of the shoe and appear as reinforcing gussets 28 which are preferably cast integrally in the angles between the uprights 6 and the cross elements 7 to reinforce the stirrups.

In lieu of the thin side webs 20, the uprights 6 are joined by thin, relatively low, connecting webs or elements 30 which are preferably cast integrally with the stirrup uprights 6. While

bottom edges 31 of the connecting elements 30 are straight and substantially flush with the bottom 10 of the wear block 5 for contacting the upper surface of the supporting tilt block 4, upper edges 32 are curved, providing reinforcing gussets 33 integrally joined to the stirrup uprights. The major portion of each of the wear block side faces 9 between the stirrups are thus exposed to the atmosphere. Longitudinally extending ribs 34 optionally may be integrally formed along the connecting elements 30, the ends of these ribs being connected to the stirrup uprights 6 and serving not only to reinforce the side structure of the shoe but also to aid in cooling of the shoe.

The opposite sides of the metal holding frames of the slider shoes of the present invention are connected only at the ends of the shoes, the entire bottom surface of each of the wear inserts being exposed for direct bearing contact with the supporting trolley head structure. The thin sections of the connecting webs permit casting the metal bodies about the wear inserts in such a manner that the webs freeze or harden before the heavier sectioned parts of the frame body, thus minimizing stresses imposed on the carbon insert by shrinkage of the cast metal.

In accordance with the patent statutes, the principles of the present invention may be utilized in various ways, numerous modifications and alterations being contemplated, substitution of parts and changes in construction being resorted to as desired, it being understood that the articles shown in the drawings and described above are given merely for purposes of explanation and illustration without intending to limit the scope of the claims to the specific details disclosed.

What I claim and desire to secure by Letters Patent of the United States is:

1. A current collector shoe comprising an elongated wear block of substantially rectangular transverse section and a metal frame embracing the block, said frame having elements extending under the block adjacent the ends of the latter, up the block sides at said ends and longitudinally of the block spaced above the top of the latter, the top of the block being open along its side edges intermediate the block ends, and metal web portions thinner than the elements disposed flatwise against the sides of the block and connected to the upwardly extending elements.

2. A current collector shoe comprising an elongated wear block of substantially rectangular transverse section and a metal frame embracing the block, said frame having elements extending under the block adjacent the ends of the latter, up the block sides at said ends and longitudinally of the block spaced above the 60

top of the latter, the top of the block being open along its side edges intermediate the block ends, and metal web portions thinner than the elements disposed flatwise against the ends and sides of the block and connected to the upwardly extending elements.

3. A current collector shoe comprising an elongated wear block of substantially rectangular transverse section and a metal frame embracing the block, said frame having elements extending under the block adjacent the ends of the latter, up the block sides at said ends and longitudinally of the block spaced above the top of the latter, the top of the block being open along its side edges intermediate the block ends, metal web portions thinner than the frame elements disposed flatwise in heat conducting relation against the block sides, and a plurality of relatively thin metal cooling fins integral with the web portions and extending between and integrally connected to the upwardly extending elements of the frame.

4. A current collector shoe comprising an elongated wear block having top, bottom, end and side faces and a cast metal body embracing the block, said body including relatively thick sectioned frame elements contacting the block across the entire width of its bottom face and over the entire height of its side faces, said body also including relatively thin sectioned web elements contacting the block faces, the areas of the block contacted by the frame elements being less than the areas contacted by the web elements.

5. A current collector shoe comprising an elongated wear block having top, bottom, end and side faces and a cast metal body embracing the block, said body including relatively thick sectioned frame elements contacting the block across the entire width of its bottom face and over the entire height of its side faces, said body also including relatively thin sectioned web elements contacting the block faces, the areas of the block contacted by the frame elements being less than the areas contacted by the web elements and spaced from one another by the web contacted areas.
